UNITED STATES PATENT OFFICE.

ALFRED G. BROWN, OF CHICAGO, ILLINOIS, ASSIGNOR TO UNION FIBRE COMPANY, OF WINONA, MINNESOTA, A CORPORATION OF MINNESOTA.

AIR-COOLED STORAGE-HOUSE.

1,295,422.

Specification of Letters Patent. Patented Feb. 25, 1919.

Application filed July 5, 1913. Serial No. 777,531.

To all whom it may concern:

Be it known that I, ALFRED G. BROWN, a citizen of the United States, residing at Chicago, in the county of Cook and State 5 of Illinois, have invented certain new and useful Improvements in Air-Cooled Storage-Houses, of which the following is a specification.

My invention relates to improvements in 10 air cooled storage structures designed particularly for the storage of fruit and for use in climates where there are generally hot days and cool nights, its object being to provide a heat insulated storage house which 15 is provided with improved means for causing and facilitating a circulation of cool outside air therethrough during the cooler hours of the night or day, and for excluding the outside air and heat during the hotter hours 20 of the day.

To this end the invention consists in the construction, combination, and arrangement of parts hereinafter described and claimed.

In the accompanying drawings forming 25 part of this specification,

Figure 1 is a floor plan of the improved house, with the grating for one of the air ducts partly broken away;

Fig. 2 is a vertical longitudinal section 30 through the house on line $w-w$ of Fig. 1;

Fig. 3 is a cross section through the house on line $y-y$ of Fig. 1;

Fig. 4 is a cross section through one of the air ducts on line $x-x$ of Fig. 1;

Fig. 5 is a cross section through a fragment of the walls, ceiling, and floor; and

Fig. 6 is a detail of the sprinkling pipes.

The building, which may be of usual 40 wooden frame or other suitable construction, is supported upon piers 2 at a height of about four feet from the ground. In it is an insulated storage chamber A which occupies the entire ground floor outside of the sorting and packing platform B which stands 45 underneath the forward gable of the building. This chamber has thoroughly heat insulated walls 3, floor 4, and ceiling 5. Where the walls, floor and ceiling are of wood, or other non-insulating material, the insulation

50 may be accomplished in any suitable way, but preferably by placing between the joists or studding and the inner and outer sheathing spaced layers of such insulating material

as quilted fiber felting, as best shown in Fig. 5, where 6 represents the floor joists, 7 the 55 ceiling joists, 8 the wall studding, and 9 the various layers of fiber felting. There can, of course, be as many layers of felting as is thought desirable, and they can be held apart from one another to form insulating air 60 spaces by means of furring strips 13 or other suitable means. It will be seen that the floor joists 6 run crosswise of the building while the ceiling joists 7 run longitudinally of the building. 65

Above the storage chamber A is an attic C in the ends of which are louvers 10 to allow the outside air to circulate through the attic. Between the chamber A and platform B is a vestibule 11 having insulated walls 70 and an insulated door 12 at each end.

Arranged under the floor of the storage chamber are one or more air ducts 14. In the form shown in the drawings there are two of these air ducts and they extend inwardly from the sides of the building nearly to the middle thereof. They are constructed in the shape of troughs, open at their top and outer ends and closed at their inner ends, and extend up through the floor of the chamber between the floor joists. At the top they are covered only by gratings 15, which allow the air to pass up from the air ducts into the chamber. These gratings preferably form a part of the flooring of the chamber. At 85 the outer end of each air duct is an insulated door or damper 16, which can be closed at will to prevent the outside air from passing through them into the chamber. The walls 90 of the air ducts, as well as the damper, are insulated in any suitable way, preferably in the same manner as the walls and flooring of the chamber, as illustrated in Fig. 4. Extending upwardly from the chamber at any suitable point or points, preferably at the 95 end or ends thereof, and passing through the ceiling 5 and the attic C are one or more ventilating chimneys 17, having at the top louvers 18 for the escape of warm air from the chamber. Arranged in the ceiling at the 100 bottom of the chimney is an insulated damper 19 adapted to close communication between the chamber and chimney.

Extending longitudinally of the air ducts 14 just under the grating 15, are a number 105 of rods 20 or other suitable supports upon

which are hung strips or sheets 21 of cloth or other material, preferably burlap, which will easily absorb and give off moisture. These strips extend lengthwise of the air ducts, as will be seen in Fig. 4, so as not to block the current of inrushing air. Suitably supported along the top edge or edges of each air duct, and extending longitudinally thereof, are one or more sprinkling pipes 22 perforated along their inner sides in order to allow water, when forced through the pipes, to be sprayed upon the upper edges of the cloth sheets. These pipes are closed at their forward ends and are provided with regulating valves 23.

Along the floor are laid pieces of scantling 24, as indicated in Figs. 1 and 2. They are preferably laid longitudinally of the chamber, at right angles with the air duct, and are spaced a sufficient distance apart to allow the fruit crates to be placed so that they will meet endwise at the middle point of the scantling. Over and across the grating are laid shorter pieces 25 of scantling, the ends of which will rest upon the tops of the longer pieces of scantling 24 laid at the sides, so that the scantlings 25 will be raised up from the grating and not block the entering air.

30 Thus, after the crates or boxes have been piled up upon the scantlings 24 and 25 as described, the cold air drawn in through the air ducts will rise up through the grating and circulate in the spaces under the crates and between the scantling, whence it will pass up around the crates piled up above.

These houses are designed particularly for use in a climate where there are cool nights and hot days, and are constructed so as to utilize the difference in temperature between day and night. The fruit, when piled and stored, may have a field heat of from 85° to 90°, whereas the night temperature in the autumn may be from 32° to 45°. The crates of fruit are first piled up in the manner described. At about nine o'clock in the evening the insulated dampers or doors in the air ducts under the floor and the air shafts in the chimneys are opened to allow the hot air and gas given off by the fruit to escape by the chimneys. This will create a partial vacuum in the otherwise tight storage room and cause the air to flow in through the grating and among the boxes. This will quickly change the air in the room and very rapidly draw the field heat from the fruit. This process is allowed to continue until about sunrise, at which time all the dampers and doors in the chimneys and air ducts are closed and shut tight, and kept closed until the next evening. By reason of the thorough insulation of the chamber, the temperature will remain through the day within a few degrees of the coldest tem-

perature reached during the preceding 65 night, no matter how hot it may be outside.

The cooling effect of the air current is much increased by the moistened burlap or cloth strips which are hung in the air ducts. When these strips are wet by the spray from 70 the adjacent pipes, the entering air will be cooled by the rapid evaporation of the moisture from the strips. This evaporation will act as an additional refrigerant to reinforce the cooling effect of the air. 75

I do not wish to limit myself to the use of any particular number of chimneys or air ducts, and where these terms are used in the claims in the singular number they will be understood in each case to mean 80 "one or more".

I claim as my invention:

1. An air cooled storage house comprising a storage chamber having an elevated floor provided with an air inlet opening extending a substantial distance across the floor, the floor, ceiling and walls of the chamber being lined with heat insulating material, an air conducting trough arranged beneath the air inlet opening for establishing communication between the interior of the chamber and the outer atmosphere, the outer end of the trough being opened, closure means for the opened outer ends of the troughs, a chimney leading from the top of the chamber to the outer atmosphere, and a closure for the chimney located adjacent the top of the chamber. 95

2. The herein-described process of cooling storage houses, consisting in providing a 100 heat insulated storage chamber, providing an air inlet in the floor of the chamber and having communication with the outside atmosphere adjacent the plane of the floor, providing an air outlet in the upper part of 105 the chamber for the escape of warm air from within the chamber, and then closing the inlet and outlet until the temperature within the chamber is higher than the outside temperature, and opening the inlet and outlet to permit of the escape of the interior warmer air through the outlet and thereby automatically induce a natural inflowing current of cooler air through the air inlet. 110

3. An air cooled storage house comprising 115 a storage chamber having an air inlet in its floor, strips of moisture absorbent material hung in the air inlet below the floor in spaced relation so as to admit of the passage of air upwardly between the strips into 120 the chamber, and a pair of sprinkling pipes arranged in opposing relation on opposite sides of the air inlet to unobstruct the passage of the air upwardly through the latter, said pipes being further arranged below 125 the floor and above the strips and provided with lateral perforations for directing a liquid across the air inlet into the strips.

4. A storage structure comprising a chamber, a ventilating chimney leading upwardly therefrom to the outer air, an air duct leading under and along the bottom of the chamber to take air below the floor level and open along its length to communication with the interior thereof, strips of moisture absorbent material hung lengthwise in the air duct and below the lengthwise openings, a sprin-

5 kling pipe arranged along the side of the 10 air duct in position to spray said strips, and a closure for the air duct.

In testimony whereof I affix my signature in presence of two witnesses.

ALFRED G. BROWN.
